ENGINE STARTING MECHANISM

Raymond P. Lansing, Montclair, N. J., assignor,
by mesne assignments, to Eclipse Aviation Corporation,
East Orange, N. J., a corporation of
New Jersey

Application October 30, 1931, Serial No. 572,210
Renewed March 11, 1935

20 Claims. (Cl. 290—38)

This invention relates to starting mechanisms and more particularly to starters for engines of the internal combustion type.

One of the objects of the invention is to provide, in an engine starter, novel means for establishing driving relation between the starter and a member of the engine to be started.

A further object of the invention is to provide a novel starter embodying engagement producing means operative upon the engine-engaging member to cause the latter to move directly into engine-engaging position prior to imparting any excessive rotary movement thereto.

A further object of the invention is to provide in a motor-driven starter of the type above described, novel means for delaying the acceleration of the motor to normal driving speed until the engine-engaging member has completed its engine-engaging movement.

20. A principal object of the invention is to provide a novel motor-driven starter mechanism of the type involving a driving member movable into engagement with a member of the engine to be started, in which means are provided for 25 preventing a return torque transmission to the motor after starting of the engine under its own power, while at the same time maintaining said driving member in position to resume the action of turning over the engine to restart it automatically in the event the engine should stall, or 30 decelerate to such a degree that a stall impends, such automatic resumption of the cranking operation being conditional (in the embodiment herein illustrated) upon the continued energization of the motor during this period of stalling tendency.

Another object of the invention is to provide in a motor-driven starter of the type in which a normally disengaged driving member is to be moved into engagement with a member of the engine to be started, novel connections for effecting such driving engagement in response to the initial rotary movement of the motor.

Other objects and advantages to be derived 45 from the use of the invention disclosed herein will become evident on an inspection of the following description when read with reference to the accompanying drawing, illustrating the preferred embodiment of the invention. It is to be 50 expressly understood, however, that said drawing is for the purpose of illustration only and is not to be construed as a definition of the limits of the invention, reference being had for this purpose to the appended claims.

55. In the drawing,

Fig. 1 is a view partly in elevation and partly in vertical section showing a device embodying the invention; and

Fig. 2 is a transverse sectional view along the line 2—2 of Fig. 1.

Referring to the drawing, the invention is shown embodied in a device having a prime mover 1, herein shown in the form of an electric motor whose armature shaft 2, extended as indicated at 3, constitutes the driving shaft of 10 the driving mechanism. A casing or bracket 4 extends from the frame of the motor and at its outer end is provided with a bearing portion 5 adapted to receive the outer end 3 of the armature shaft. The casing also preferably constitutes the supporting means for a shifting lever 6 to be further described, the said lever being pivoted to the casing by suitable means such as rock shaft 1, on which is also mounted a yoke portion 8 (shown best in Fig. 2) whose lower end 9 is in a position to engage a flanged collar 10 constituting part of the shifting means herein-after described, and operative to mesh the driving member 11 with the engine member 12, the former being shown in the embodiment herein 25 illustrated as a pinion movable along the shaft 3 into mesh with the gear 12 drivably connected by suitable means not shown, to the crankshaft.

The novel means for swinging the lever 6 to effect a meshing of the pinion 11 with the gear 12 includes a link 14 pivotally connected at one end to the upper end of the lever 6 and at its other end to a second lever 15, the latter being adapted to swing about a fixed pivot 16 journaled in a relatively stationary support, the lower 35 end of the lever terminating in a yoke 17, the lower ends of which engage a flanged collar 18 in substantially the same kind of connection as that between the members 9 and 10 above described. As shown the flanged collar 18 is an 40 integral extension of an internally threaded sleeve or nut 19 movable to a limited extent along an externally threaded sleeve 20 keyed as at 22 to the outer end 21 of the armature shaft 2. The extreme end of the portion 21 of the armature 45 shaft has threaded thereto a stop nut or abutment 23 having a flange 24 providing a seat for a coiled compression spring 25, the opposite end of which bears against the shoulder 27 formed on the nut 19 at the junction of the collar portion 18 with the threaded portion. The normal stress of the coil spring 25 is preferably such as to maintain the nut 19 in abutting relation to a collar 30. This coil spring 25 is also of sufficient strength to return the nut 19 from the dash 55

line position indicated in Fig. 1 to the full line position, against the frictional load on the motor shaft 2 when the latter is de-energized, the lead of the threads of the nut 18 and sleeve 20 being sufficient to permit such a longitudinal shifting of the nut, it being understood that such shifting will effect a movement of the motor shaft 2 through an arc of length corresponding to said lead, and in a direction opposite to the direction of rotation of the motor when energized. The collar 30 abuts a thrust bearing 31 received in the boss 32 of the casing of the motor 1. If desired, the end of the yoke 17 may be provided with suitable means, herein shown in the form of leaf springs 33 secured to the yoke ends, and frictionally engaging the radial surfaces of the flanges on the collar 18 to insure a longitudinal movement of the nut 18 in response to initial rotation of the sleeve 20, and to prevent any rotary movement of the nut prior to the completion of the predetermined amount of longitudinal movement.

The invention further includes, as above indicated, novel means for producing first, a relatively slow rotary movement of the motor shaft 2, and thereafter an acceleration thereof in response to the action of the linkage above described. As shown, such means include an initial relatively high resistance circuit through the field coils 35 of the motor and a second lower resistance circuit thereto, the latter being closable by switch means operating only after the linkage has shifted to a predetermined extent in response to the above described screw action between the members 19 and 20. Referring to the electrical connection superimposed schematically on the mechanical parts of Fig. 1, the initial higher resistance circuit includes a pair of conductors 37 and 38, the former terminating from a suitable source of current 39 and the latter leading to a terminal contact 40 constituting one of a pair of contacts 40 and 41 normally electrically separated but adapted to be abridged by a movable contact 42 located at the lower end of a pin 43 normally held in the position indicated in Fig. 1 by the action of a compression spring 44 having abutting relation at one end with a recessed ledge formed on the switch casing 45, and at the other end with a collar or head 46 attached to the pin 43 and terminating in a rounded projection 48 adapted to be contacted by the correspondingly rounded end 49 of a striker piece or finger 50 connected to or integral with the yoke 8 above described so as to oscillate with the lever 6 in response to actuation thereof through the mechanical connections above described. The terminals 40 and 41 are electrically connected in a circuit 51 in which there is inserted a resistance unit 52, and leading from the contact 41 is another lead 53 completing the positive side of the circuit from the source 39 to the windings of the motor upon closure of the switch 54, the latter being located on the control panel of the vehicle or in some other position equally accessible to the operator. As shown, the brushes 59 of the motor are yieldably and removably held in position by means of spring 60 and removable insulating yokes 61, but this mounting forms no part of the present invention and it is to be understood that the motor construction may be varied as desired.

The means for drivably connecting the collar 18 with the engine-engaging pinion 11 to first move the latter into mesh with the engine member 12 and thereafter turn over the engine crank-

shaft in response to the torque transmitted through such driving connections, is herein shown as constituted by an assembly of parts adapted to respond to rotation of the motor shaft 2, such assembly of parts including preferably an axially 5 movable overrunning clutch mechanism constituted by a plurality of rollers 65 disposed in tapering recesses cut at regular intervals along the outer surface of a sleeve 67 splined to the armature shaft as indicated at 68, the sleeve 67 thus 10 constituting an inner race of the clutch, the outer race being constituted by a member 70 having an inwardly turned annular termination 71 to aid in maintaining the rollers 65 in position and having at its opposite end a radial projection 15 or flange 72 adapted to be held in abutting relation to the inwardly turned flange 73 on the collar 18 by force of a coiled compression spring 74 one end of which presses upon the opposite side of the flange 72 and the other end of which abuts 20 a disc 77 held fast to the pinion 11 by any suitable means which as shown consists in cutting a peripheral groove near the end of the pinion and then peening over the end of the pinion as indicated at 78. The disc 77 also abuts an inwardly turned end 80 of a barrel 81, a portion of the cylindrical surface of which is cut away at regular intervals to provide a slotted or splined effect, the slots 82 thus formed being adapted to register with the inwardly turned flange 73 above 30 described, the latter having cut out portions therein to correspond to the cuts in the barrel 81. In order to prevent separation of the members 70 and 18 from the barrel 81, a split collar 35 85 with radially projecting fingers 86 is sprung outwardly into corresponding slots in the barrel 81. A collar 87 is secured to the member 70 by suitable means such as screws 88 to maintain the rollers 65 in position relative to the inner race 67, and is in turn held against displacement to 40 the right as viewed in Fig. 1 by reason of its engagement with the shoulder 89 formed on the shaft 2 at the point of termination of the splines 68.

In operation, the closure of the switch 54 produces an initial energization of the motor which due to the comparatively high resistance 52 imparts only a comparatively slow rotation of the shaft 2. This rotation, however, is sufficient to cause a longitudinal displacement of the nut 18 50 from the position shown in full lines in Fig. 1, to the position indicated in dash lines, in which latter position its motion in a longitudinal direction is arrested by the energy stored in the now compressed spring 25. Such motion however is 55 sufficient to draw the link 14 to the right and lever 6 in a clockwise direction to advance the pinion 11 into mesh with the gear 12, the endwise pressure on the pinion being exerted through yoke 8, collar 18, flange 72 of the clutch member 70, spring 74 and disc 77. At the same time the contact 42 is moved toward the terminals 40 and 41 by engagement of finger 50 with the rounded projection 48, the spacing between the latter two members and between the contacts 65 being such that the contacts do not engage until the teeth of the gears 11 and 12 are well in mesh. On bridging the contacts 40 and 41 by the member 42, the comparatively high resistance 52 is shunted out of circuit to the motor, whereupon shaft 2 is accelerated and a high degree of rotation is imparted to the pinion 11 through rotary driving connections constituted by the inner race 67 of the overrunning clutch, the rollers 65 which are in the counter-clockwise direction 70 75

of rotation move into wedging relation to the outer race 70, the drive from the member 70 being direct to the pinion by way of the splines 82 and 78 at the opposite ends thereof. When the engine starts, the resulting superior driving torque of the gear 12 accelerates the pinion 11 but there is no return drive to the motor shaft 2 even though the pinion remains in mesh with the gear, the overrunning action of the rollers 65 of the clutch allowing the outer race 70 thereof to revolve independently of the inner race 67 splined to the motor shaft and even though the operator should allow the switch 54 to remain closed. When the latter switch is eventually opened, the resulting de-energization of the motor and deceleration of the shaft 2 permits the spring 25 to return the nut 19 to its normal position in abutment with the stop 30, such return movement causing a disengagement of the pinion 11 from the gear 12 through axially directed pull exerted thereon in the following manner: the lever 6 pushes collar 10 to the right, which in turn pushes the split collar 85, the latter having its teeth 86 interconnected with the corresponding slots in the barrel 81 causes the latter, and hence the pinion 11, to move correspondingly to the right, thus returning the parts to their normal positions as indicated in Fig. 1.

In the event that the teeth of pinion 11 strike those of the engine member 12 during the forward meshing movement of the former, the resulting compression of spring 74 upon its seat on annular discs 77 will permit completion of the shifting movement of the lever 6 and consequently will permit closure of the shunt circuit through the contact 42. The resultant acceleration in the shaft 2 will move the rollers 65 into driving relation to the outer race 70 and will thus cause sufficient rotary movement of pinion 11 to bring its teeth into proper registry with the teeth of the member 12. Thereupon the previously compressed spring 74 will become effective to snap the pinion into full meshing engagement with the gear 12 and thus establish cranking relation.

From the foregoing it is apparent that the invention provides means for producing driving engagement between the starter and the engine prior to full energization of the driving means, together with means for preventing a return torque transmission to the motor even though the driving member of the starter remains in operative engagement with the engine after starting of the latter under its own power. Moreover, the novel shifting means disclosed make it possible to divide the shifting and driving apparatus into separate locations on either side of the prime mover, thus reducing the overhang between the engine end of the prime mover and the engine. A further advantage possessed by the invention is the elimination of the necessity of forcing the pinion into driving position by muscular effort, the energy of the initial rotation of the starter being utilized for such purpose. A further advantage possessed by the invention is the elimination of disengaging springs or other torque responsive devices which in the constructions heretofore employed were necessary to prevent injury to the starter as a result of the increased torque developed in the engine on starting. With constructions employing the principles of the present invention, there is no danger of injury, regardless of the length of time the operator delays in reopening the switch 54. In fact it is desirable for the operator to delay the

opening of the switch 54 for a brief period following the apparent starting of the engine, for it is well known that engines frequently stall just after the initial firing impulse, and therefore an opening of the switch 54 after such initial firing impulse might be premature. This is particularly true when the engine is accelerated by an isolated firing impulse, and in such cases the overrunning of the starter by the engine is merely temporary. Therefore I prefer to maintain the motor circuit closed for a rather considerable period, so that the pinion 11 will remain in a position to resume the drive, in contra-distinction to devices of the prior art wherein the pinion is immediately demeshed by the overrunning action due to the first firing impulse, with the result that the subsequent efforts to remesh produce a bumping action known as "hunting", and an attendant severe stress on the mechanism.

From the foregoing explanation it is evident that the feature of the invention whereby the pinion may overrun the motor shaft is of considerable importance in that it makes it possible to restart the engine through application of power to the flywheel 12 in the event that the engine tends to stall immediately after the first firing impulse, and prior to release of the switch 54. In this connection it may be noted that the invention may be made applicable to, and may be combined with any of the existing types of electrical or electro-magnetic control mechanism operating through the engine ignition circuit, or other current generating circuit to re-engage the starter with the engine on any subsequent tendency to stall, that is, any stalling tendency which occurs after the switch 54 has been opened.

While it is obvious from the foregoing that the embodiment herein disclosed possesses practical merit, it is to be understood that this embodiment is not exclusive of other embodiments which may incorporate the novel provisions herein disclosed and claimed, while other embodiments will be suggested to persons skilled in the art on examination of the foregoing description and the accompanying drawings.

It is to be understood that various other changes may be made in the construction, arrangement and interrelation of the parts constituting the invention without departing from the spirit thereof, the extent of the permissible variations being ascertainable by reference to the appended claims.

What is claimed is:

1. In apparatus of the class described, an engine driven member, an electric motor having a driving shaft, a motor-driven member driven therefrom and normally out of engagement with said engine member, means for moving said motor-driven member into engagement with said engine member, means for disengaging said motor-driven member, means for rendering said disengaging means ineffective prior to de-energization of said electric motor, and an overrunning clutch mechanism facilitating re-acceleration of the engine member in the event that the latter loses momentum after the initial firing impulse of the engine, but prior to de-energization of the electric motor.

2. In combination with an internal combustion engine having a part to be engaged mounted thereon, an electric starting motor, a source of current, a toothed member adapted to be driven from said motor and normally out of mesh with said part to be engaged, means responsive to the initial rotation of said motor to move said

- toothed member into mesh with said part to be engaged, and means for automatically increasing the electrical energy delivered to said motor from said source as said toothed member reaches its meshed position, said last named means comprising a relatively high resistance circuit to said motor and means for shunting a portion of said circuit in response to movement of said toothed member.
3. In combination with an internal combustion engine having a gear mounted thereon, an electric starting motor, a source of current, a gear engaging member adapted to be driven from said motor and normally out of mesh with said gear, means responsive to initial rotation of said motor to move said gear engaging member into mesh with said gear, means for connecting said source with said motor to develop driving power therein to a degree sufficient to mesh said gear engaging member with said gear but insufficient to crank the engine, and means operable automatically on the completion of the meshing movement to increase the power developed in said motor.
4. In combination with an internal combustion engine having a gear mounted thereon, an electric starting motor, a source of current, a gear engaging member adapted to be driven from said motor and normally out of mesh with said gear, means responsive to initial rotation of said motor to move said gear engaging member into mesh with said gear, means for connecting said source with said motor to develop driving power therein to a degree sufficient to mesh said gear engaging member with said gear, but insufficient to crank the engine, and means operable automatically on the completion of the meshing movement to increase the power developed in said motor, said last named means comprising a second circuit from said source to said motor of lower resistance than said first named circuit, said second circuit being closable by a member movable with said gear engaging member.
5. In an engine starting mechanism, a driving motor, a rotatable shaft projecting from said motor at both ends thereof, a driving member mounted on one end of said shaft for longitudinal movement thereof and rotary movement therewith and adapted to cooperate with and drive a member of the engine to be started, a control member mounted on said shaft at the opposite end of said motor for longitudinal movement thereof and rotary movement thereon, and a driving connection between said two members.
6. In an engine starting mechanism, a driving motor, a rotatable shaft projecting from said motor at both ends thereof, a driving member mounted on one end of said shaft for longitudinal movement thereof and rotary movement therewith and adapted to cooperate with and drive a member of the engine to be started, a control member mounted on said shaft at the opposite end of said motor for longitudinal movement thereof and rotary movement thereon, and a link mechanism extending over the length of said motor into driving relation with both said driving and control members.
7. Engine starting mechanism comprising a driven member, a motor having a driving shaft provided with a threaded portion projecting from said motor on the side remote from said driven member, and an unthreaded portion projecting from said motor on the side adjacent said driven member, a driving member on said unthreaded portion, said driving member being normally out of engagement with said driven member, and means mounted on said threaded portion of said shaft for causing the driving member to engage said driven member.
8. Engine starting mechanism comprising a driven member, a motor having a driving shaft provided with a threaded portion projecting from said motor on the side remote from said driven member, and an unthreaded portion projecting from said motor on the side adjacent said driven member, a driving member on said unthreaded portion, said driving member being normally out of engagement with said driven member, means mounted on the threaded portion of said shaft for causing the driving member to engage said driven member, and means yieldably connecting said last named means with said driving member.
9. Engine starting mechanism comprising a driven member, a motor having a driving shaft provided with a threaded portion remote from said driven member, an unthreaded portion adjacent said driven member, a driving member on said unthreaded portion, said driving member being normally out of engagement with said driven member, means mounted on said threaded portion of said shaft for causing the driving member to engage said driven member, said last named means comprising a threaded sleeve operatively engaging said threaded portion, and a combined link and spring mechanism connecting said sleeve with said driving member.
10. Engine starting mechanism comprising a driven shaft having a gear secured thereto, a motor having a driving shaft provided with a threaded portion projecting from said motor on the side remote from said driven shaft, and an unthreaded portion projecting from said motor on the side adjacent said driven shaft, a gear engaging member on said unthreaded portion, said gear engaging member being normally out of mesh with said gear, and means mounted on said threaded portion of said shaft for causing the gear engaging member to mesh with said gear, said last named means comprising a threaded sleeve operatively engaging said threaded portion, and means yieldably connecting said sleeve with said gear engaging member.
11. Engine starting mechanism comprising a driven shaft having a gear secured thereto, a motor having a driving shaft provided with a threaded portion projecting from said motor on the side remote from said driven shaft, an unthreaded portion projecting from said motor on the side adjacent said driven shaft, a gear engaging member on said unthreaded portion, said gear engaging member being normally out of mesh with said gear, means mounted on said threaded portion of said shaft for causing the gear engaging member to mesh with said gear, said last named means comprising a threaded sleeve operatively engaging said threaded portion, and a combined link and spring mechanism connecting said sleeve with said gear engaging member.
12. In combination with an internal combustion engine an electric starting motor, a circuit for said motor including a resistance, movable connecting means for said motor and engine, means for closing said circuit with the resistance therein, and means responsive to a predetermined degree of rotation of said motor for moving said connecting means into operative position and then cutting said resistance out of said circuit, said last named means comprising a second circuit from said source to said motor of lower resistance than said first named circuit, said sec-

- ond circuit being closable by a member movable with said connecting means.
13. In combination with an internal combustion engine, an electric starting motor, a circuit for said motor including a resistance, movable connecting means for said motor and engine, means for closing said circuit with the resistance therein and means responsive to a predetermined degree of rotation of the motor for cutting said resistance out of said circuit, said last named means comprising a second circuit from said source to said motor of lower resistance than said first named circuit, said second circuit being closable by a member movable with said connecting means.
14. In combination with an internal combustion engine having a gear mounted thereon, of an electric starting motor, a source of current, a gear engaging member adapted to be driven from said motor and normally out of mesh with said gear, means responsive to the initial rotation of said motor to move said gear engaging member into mesh with said gear, and means for automatically increasing the electrical energy delivered to said motor from said battery as said gear engaging member reaches its meshed position, said last named means comprising a second circuit from said battery to said motor of lower resistance than said first named circuit, said second circuit being closable by a member movable with said connecting means.
15. In an engine starting mechanism, a driving motor, a rotatable shaft projecting from said motor at both ends thereof, a driving member mounted on one end of said shaft for longitudinal movement thereof and rotary movement therewith and adapted to cooperate with and drive a member of the engine to be started, a control member mounted on said shaft at the opposite end of said motor for longitudinal movement thereof and rotary movement thereon, a link mechanism extending over the length of said motor into driving relation with both said driving member and said control member, a control switch for said motor, and means movable with said link mechanism for operating said control switch.
16. In combination with an internal combustion engine, an electric starting motor therefor, movable connecting means for said motor and engine, a source of current and connections for operating said motor, and means responsive to a closure of the circuit through said connec-
- tions for automatically moving said connecting means into operation and thereafter imparting a greater supply of working energy to said motor.
17. In combination with an internal combustion engine, an electric starting motor, a circuit for said motor including a resistance, movable connecting means for said motor and engine, means including a single actuating member for actuating said connecting means and closing said circuit with said resistance therein, and means responsive to a predetermined degree of rotation of the motor for cutting said resistance out of said circuit.
18. In combination with an internal combustion engine, an electric starting motor, a circuit for said motor including a resistance, movable connecting means for said motor and engine, means for closing said circuit with said resistance therein, and means responsive to a predetermined degree of rotation of said motor for moving said connecting means into operative position and then cutting said resistance out of said circuit.
19. In combination with an internal combustion engine having a gear mounted thereon, an electric starting motor, a source of current, a gear engaging member adapted to be driven from said motor and normally out of mesh with said gear, means responsive to the initial rotation of said motor to move said gear engaging member into mesh with said gear, and means for automatically increasing the electrical energy delivered to said motor from said source as said gear engaging member reaches its meshed position.
20. Engine starting mechanism comprising a motor having an armature and a field coil frame, a shaft driven by said motor and extending a considerable distance beyond the field coil frame, but substantially coaxial with the armature, an engine engaging member slidable along, and rotatable with said shaft, the latter having axially extending surfaces cooperating with said engine engaging member to insure rotation of said engine engaging member in response to rotation of said shaft, and means for causing said engine engaging member to slide along said shaft into engine engaging position, said means including a control element movable with the motor armature and a combined link and spring mechanism operating to mesh said engine engaging member in response to the initial movement of said control element.

RAYMOND P. LANSING.
